UNITED STATES PATENT OFFICE.

HENRY M. PIERCE, OF NASHVILLE, TENNESSEE.

PROCESS OF MANUFACTURING COKE.

SPECIFICATION forming part of Letters Patent No. 330,731, dated November 17, 1885.

Application filed July 31, 1884. Serial No. 139,263. (No model.)

To all whom it may concern:

Be it known that I, HENRY M. PIERCE, a citizen of the United States, residing at Nashville, in the county of Davidson and State of Tennessee, have invented certain new and useful Improvements in Processes of Manufacturing Coke; and I hereby declare the following to be a full, clear, and exact description of the same, reference being had to the accompanying drawings, which form a part of this specification, showing the preferred means adapted to carry out the method.

The method commonly practiced in this country for the manufacture of coke consists in the use of small mound-shaped ovens about ten (10) feet in diameter at the base, and adapted to hold a charge of about four (4) tons, or one hundred (100) bushels. The firing is done at the top and the coking process proceeds from above downward, first supported by combustion of the upper layer of coal, and afterward by the volatile matter and gases evolved from the deeper layers, and which becomes ignited and burns in the upper or vacant portion of the oven. The air to support combustion is admitted in limited quantities by means of ports or around the top of the coke-oven door. The difficulties encountered by this method are, first, loss from the per cent. of coal consumed in the early stages of the process; secondly, loss from the imperfectly-cooked mass which remains in the oven; thirdly, the loss from or waste of the large percentage of the heating-power of the volatile matters, gases, &c., which burn in the upper part of the oven and as a result thereof; fourthly, the unequal heating of the oven, and the unnecessarily slow progress of the coking.

To avoid the cost entailed by the use of small ovens, and in a measure the loss from the imperfectly-cooked mass remaining in the bottom of the ovens, large kilns open at the top have been employed, and the coking process conducted by cross-firing and by proceeding from below upward, for which purposes a series of horizontal air and draft flues were constructed in the bottom of the charge; but by this method, though the limitation of the charge was avoided, the loss from consumed coal still resulted, and the loss of the heating value of the gas and volatile products was augmented.

A third mode of procedure has been to em-

ploy a series of vertical retorts surrounded by combustion-flues wherein the gas evolved from the coking-charge was burned to heat 55 the retort and perform the coking. By this means, while the heating value of the evolved gas, &c., was saved, the capacity of the oven and plant was limited with all its attendant cost and disadvantages, save the unequal heating 60 of the charge.

Having above pointed out the methods commonly practiced and the means employed, I will now first indicate generally the character of my invention, and then describe specifically the best manner now known to me of carrying it into effect. Its objects are to avoid loss of fuel by direct combustion of any portion of the charge, therefore I conduct the process by radiated heat; secondly, 70 to utilize all the heating value of the evolved gases, consequently I utilize said gases as the fuel for producing the heat to heat the whole charge uniformly, and at the same time avoid the deposit of tarry matter and the formation 75 of an imperfectly-cooked mass at the bottom of the charge and the attendant loss, so I apply the radiated heat at the bottom of the charge; and, finally, to avoid limiting the size of the charge to be treated, and this 80 results as a sequence of applying the heat at the bottom of the charge. Therefore the method may be generally stated as conducting the coking process by means of radiated heat applied to the base or bottom of the charge or 85 mass, said heat being produced by the combustion of the volatile vapors and gases evolved from the charge during the coking process.

I will next describe the apparatus which I have devised for the purpose.

In the drawings, Figure 1 is a perspective view of a battery of several coke-ovens, constituting a plant or works. Fig. 2 is a vertical longitudinal section of an oven and its appendages. Fig. 3 is a horizontal section on the line *x* *x*, Fig. 2, showing the charge or coking chamber. Fig. 4 is a similar section on the line *y* *y*, Fig. 2, showing the main combustion-chamber and radiating or branch combustion-chamber.

Like letters refer to like parts wherever they occur.

A A A indicate a series of ovens of like character arranged in battery. Each oven is

by preference of a rectangular or quadrilateral form, having its outer walls of brick or stone, with a lining of fire-brick, if preferred, and, if found necessary, a packing or dead air space between the outer wall and lining, as in constructing some classes of blast-furnaces. In size it generally exceeds an ordinary coke-oven, having a capacity of, say, from forty to sixty tons, being practically limited only by the convenience of the manufacture. At the bottom, and extending longitudinally, (and preferably centrally from end to end,) is an arched flue, tunnel, or combustion-chamber, B, from which at short intervals extend transverse branches b, which terminate in lateral collecting-flues C, leading to suitable chimneys, c. The number and arrangement of the branches b will be such as to form, practically, a hollow hearth or bottom for the whole oven. The chimneys c may be of triangular form and occupy the corners of the oven, thus saving space and giving to the oven an interior form, which facilitates the withdrawal of the coke.

Directly over the combustion-chamber B and its branches b is laid the floor of the coking-chamber. At each end of the oven A are two or more doors, a a, through which the oven may be charged and the coke withdrawn when the coking process is finished, and separating the doors or occupying the space between the same at each end of the oven is situated a chamber, also of triangular cross-section, and forming a dead-air space extending from the floor to the roof of the coking-chamber.

It will be observed that the triangular form of the chimneys c and chamber c' economizes space, and at the same time frees the oven of corners or pockets, which might not be readily accessible when removing the coke. Each chimney may be provided with a steam-jet to induce a draft therethrough when desired.

In the crown or arch of the oven are two or more gas-ports, a', which may be also used as charging-ports for introducing coal when desired. These ports are provided with stoppers for closing the same when not in use.

In the end walls of the oven, just below the crown or arch, one or more at each end, are gas-pipes d, provided with valves d' and delivering into a receiving-main, D. In this pipe d, just beyond the valve d', is arranged a steam-jet, e, which may be supplied with steam from any suitable source; and extending from the receiving-main D at a point opposite the pipe d is a valved cross-pipe, d', which connects with a delivery-main, E, from which a branch gas-pipe, d', provided with a steam-jet, projects into the combustion-chamber B. The function of the steam-jets in the pipes d and d' is respectively to act as ejectors and injectors of the combustible gases. This construction is preferably applied to each end of the furnace, as shown in Fig. 2, so that the heat may be uniformly distributed through the passages b.

When a single oven A is employed, the receiving-main D and delivery-main E may be

dispensed with, and the pipes d d' d' may be consolidated and have but a single steam jet and valve.

7c

The above description, which has been limited to a single oven, is to be understood as applying to each oven of the series shown.

I will next describe the arrangement and connection of ovens when a series or plant is employed.

Any number of ovens A, according to the size of the ovens and the capacity of the desired works, are arranged in line in juxtaposition, and the gas exits or pipes d of each oven 8c are connected with receiving-mains D, which extend the length of the battery. There are also delivery-mains E (one for each side of the battery, as is the case of the receiving-mains D) extending the length of the battery 85 parallel with and below the receiving-mains, and these mains are connected with the gas-pipes d'. Where the volatile vapors and gases evolved from the coking coal are to be used in the condition in which they come from the 90 ovens, the receiving-mains D may be connected directly with the delivery-mains E by the by-paths F alone; but as it is sometimes desirable to eliminate from the gases evolved in the oven the ammonia, &c., a condenser or scrubber, G, may be interposed between the receiving-main D and the delivery-main E, so that the gas, &c., can be used in natural condition or after treatment, as preferred.

The devices being substantially of the character hereinbefore specified, the process will be conducted as follows: The ovens are duly charged with the coal to be coked, and where the plant is first or originally put in operation the charge is heated by radiated heat from a 105 fire kindled in the combustion-chamber B, the gas-ports a' are opened, and, the fire being urged, the vapors, gases, &c., are permitted to escape at a' until they are found to be of an inflammable character. When this occurs, 110 the valves d' of pipes d are opened and the ports a' closed, which permits the evolved gases, &c., to enter the receiving-main D. Jet e may then be started, (the valve in cross-pipe d' being open,) and the gas forced directly from the oven through pipes d d' d' 115 into the combustion-chamber B, (at each end of the oven,) where, being ignited, it burns, developing an intense heat, which is distributed through the various branch flues b 120 under the whole coking-chamber, and radiates into the base thereof, the gases evolved from the charge serving to convey the heat into the upper layers thereof, so that the coking process progresses upward from below 125 rapidly and uniformly until the whole charge is coked. Toward the close of the coking process, if it is desired to expedite matters and insure the perfect coking of the upper layer, the steam-jet e and damper d' in pipe d may 130 be closed, so as to cut off the oven from the receiving-main D. The ports a' may be then opened, and the gas remaining in the top or upper part of the kiln may be ignited therein,

so as to apply a more direct and immediate heat to the upper layer of the charge; or where the ovens are worked in batteries, as shown in Fig. 1, the valves of the cross-pieces 5 d^2 may be closed, and the gas, after entering the receiving-main D, may pass the length thereof and into delivery-mains E, either directly by the by-paths F or after passing through the condensers, scrubbers, &c., at G.

10 As each chimney c is provided with a steam-jet and a damper, (which are not shown, as they can be of any common and well-known character,) in case the coking should be progressing more rapidly at one part of the 15 coking-chamber than at another, the jets can be temporarily turned off and the chimneys closed on that side or portion, and the whole or larger part of the heating-flame turned under that portion of the coking-chamber 20 where the process is progressing more slowly, and thus the balance or equilibrium can be restored. This advantage is one of the incidents of heating by radiation through base-flues of the general character specified.

25 As the various pipes and mains d , d^2 , d^3 , D, and E are provided with suitable valves, steam jets, and connections, as hereinbefore specified, it is apparent that any one or more of the ovens can be cut out of the series when 30 it is to be charged or the coke withdrawn; that when the battery has once been put in operation that operation can be continuously maintained without other fuel than the gas evolved from the coal in the coking process, and that any oven may be heated either by 35 the gas evolved therein or by gas from the other ovens of a battery, and consequently the ovens, though arranged in battery, may be operated independently.

I do not herein claim the apparatus described, as the same is made the subject-matter of a separate case, Serial No. 160,933, filed April 1, 1885.

Having thus set forth the nature, advantages, and operation of my invention, what I claim, and desire to secure by Letters Patent, is—

1. As an improvement in the manufacture of coke, the method of conducting the furnace operation which consists in first carrying on 50 the coking process by radiated heat until a stage near the completion of the process, and then firing the evolved gas in the chamber above the charge and completing the coking by the heat therefrom, substantially as and 55 for the purposes set forth.

2. As an improvement in the art of manufacturing coke, the method of conducting the furnace operation which consists in heating the charge by radiation until inflammable 60 gases are given off, then leading said gases beneath the floor of the coking-chamber and burning them therein, thereby coking the under layers of the charge by radiated heat, and finally shutting off the flow of gases to 65 the under combustion-chamber and burning them in the top of the kiln, thereby coking the top layers of the charge by direct heat, substantially as described.

In testimony whereof I have affixed my signature, in presence of two witnesses, this 28th day of July, 1884.

HENRY M. PIERCE.
